FREDERIC E. WELLS, OF GREENFIELD, MASSACHUSETTS.

FLEXIBLE DIE-HOLDER.

1,083,040.

Specification of Letters Patent. Patented Dec. 30, 1913.

Application filed April 3, 1913. Serial No. 758,597.

To all whom it may concern:

Be it known that I, FREDERIC E. WELLS, a citizen of the United States of America, residing at Greenfield, in the county of 5 Franklin and State of Massachusetts, have invented new and useful Improvements in Flexible Die-Holders, of which the following is a specification.

This invention relates to improvements in 10 die-holders.

The object of the invention is to provide a device for holding or mounting the thread-forming tool or die, as it is called, so that the same may automatically yield or move 15 slightly in any direction in case the axis of the die is not in alinement with the axis of the work on which a thread is to be formed. The present method of using a thread-forming die is to mount the same 20 in a fixed support, as in the turret-head of a screw-cutting machine, and feed or move this head toward the work that is mounted on and rotated by the mechanism contained in the head stock of the screw-cutting machine. 25 This method is objectionable for the reason that it often occurs that the axis of a piece of work on which a thread is to be cut is not in exact alinement with the axis of the die that is fixedly secured in the 30 turret-head of the machine.

The present invention is designed to provide means for flexibly mounting the die in its holder, whereby it may readily and automatically yield or move in any direction 35 a distance to compensate for the imperfect alinement of the axis of the die and work.

The device for flexibly mounting the die embodied in the present invention permits 40 it to readily follow the stock in any direction or angle, whereby a better thread will be formed than in the present method of rigidly mounting the die.

Referring to the drawings forming a part 45 of the present invention,—Figure 1 is a longitudinal sectional view, taken on the line 1—1 of Fig. 2, of the die and its holder and showing the loose pivotal support or mounting of the die, also the flexible or 50 yielding device to permit the die to move about its pivotal mounting; Fig. 2 is a longitudinal sectional view taken on the line 2—2 of Fig. 1 through the axis of the die and its holder and at right angles to that 55 shown in Fig. 1; and Fig. 3 is a top plan view showing in dotted lines the die after

it has moved a slight distance axially of its supporting trunnions.

In detail, *a* designates the hollow shank portion which is formed with an opening *b* therethrough to receive the work or stock on which a thread is to be cut. Formed integral with the shank *a* is a head-member *c* having two arm-members *d* and *e*. The thread-forming die is indicated at *f* and the 60 collet-member in which the die is secured is indicated at *g*. The collet is also formed with an opening *h* which registers with the opening *b*. The head *c* is formed with two ledge portions *i* and *j*. 65

k designates a spring that is located between the lower edge *m* of the collet and the ledge portions *i* and *j*. This spring is formed with an opening *o* in line with the opening *b* in the shank and the opening *h* 70 in the collect - member *g*; also two smaller openings on opposite side of the opening *o* to receive the two pins *p* and *q*. The spring *k* is formed with a flat portion *r* which engages the underside *m* of the collet-member 75 and oppositely - extending foot - portions *s* which engage the ledge portions *i* and *j*,—the portions *r* and *s* being connected by the inclined portions *t*, all as clearly shown in the figures. 80

In order to loosely and pivotally support the collet-member, two oppositely-located pivotal supports *u* and *v* are threaded in the arm-members *d* and *e*; their inner ends being turned down to form bearings which 85 enter diametrically-located openings *w* and *x* in the collet-member. These openings, it will be noticed, are made larger than the turned-down portions *y* and *z* of the pivotal supports *u* and *v* so as to permit the collet-member to move upward by the action of the spring *k* pressing against the underside thereof; the loose connection between the portions *y* and *z* and the openings *w* and *x* being clearly indicated in Fig. 1. It 90 should be observed also that the collet-member *g* can slightly move endwise on the portions *y* and *z*, as indicated by the spaces 3 and 4, so that the die mounted therein can automatically aline itself to agree with the axis of the stock on which a thread is being cut. When the die is used to cut a thread and the axes of the work and die do not exactly correspond, it is clear that the die can freely and automatically move in 95 any direction so as to aline itself with the axis of the stock, whereby a much better 100

thread will be cut than in the methods now employed, wherein the collet is retained in a fixed position. In fact, the collet and die can follow an elliptical path, if necessary, 5 during the thread-forming operation.

What I claim is,—

1. A collet-mounting for a die comprising a support therefor, of trunnions in the support and entering enlarged openings in the 10 collet, means to normally move the collet to cause the trunnions to engage one side of the enlarged openings, whereby the die will automatically aline itself with the axis of the stock on which a thread is being 15 formed.
2. In a mounting for a die, of means to permit the same to automatically move in any direction transverse to the axis of the die, said means comprising a loose trunnion 20 connection between the collet in which the die is mounted and its supporting member, and a spring located between the collet and the supporting member to normally force

the collet in an outward direction, as described. 25

3. A mounting for a thread-forming member, comprising a support therefor, a collet to receive said member, trunnions in the support and entering enlarged openings in the collet, the support having ledges 30 thereon, a spring engaging the ledges and the collet to force the latter against the trunnions, pins in the collet and arranged to enter openings formed in the spring to position the latter, the spring having a centrally located opening in alinement with the axis of the support, and the trunnions being formed to permit endwise movement of the collet on the trunnions, whereby the collet member may automatically yield in any 35 direction transverse to the axis of the collet when a thread is being formed. 40
